GRID ELECTRODE SUPPORT

Lynn Goodale, Newark, N. J., assignor to Federal
Telegraph Company, Newark, N. J., a corpora-
tion of California

Application February 10, 1939, Serial No. 255,593

7 Claims. (Cl. 250—27.5)

My invention relates to vacuum tube electrode supporting structures and more particularly to a supporting structure particularly adapted for supporting grid or anode electrodes of a vacuum tube.

In vacuum tube construction it is desirable that the tube be so made that the parts may be easily assembled and once assembled that the structure will be rigid and strong so that parts may not be easily dislodged, causing failure of the vacuum tube. In such tube structures it is necessary that the electrodes be supported inside the tube envelope generally by means of insulating supports made of glass or other material which will not stand a great deal of load under tension, but which will stand considerable compression load.

In accordance with my invention I provide an electrode supporting arrangement which has substantially only to withstand compression forces and not tension forces. Furthermore, I so construct my electrode supporting arrangement that there is only a small degree of torque upon the insulating members even when a tube is utilized in horizontal position.

It is a principal object of my invention to produce a vacuum tube electrode supporting arrangement which is easily constructed and is strong when once assembled.

It is a further object of my invention to provide a vacuum tube electrode supporting arrangement in which the electrode members produce mainly compression stresses upon the insulating support.

It is a further object of my invention to provide an electrode supporting structure in which the electrodes are clamped thereto by means of a simple clamping mechanism.

It is a further object of my invention to provide an electrode supporting member of insulating material on which are provided substantially spherically shaped elements for clamping the electrode thereto.

Other and more specific features and objects of my invention will be apparent from the particular description made with reference to the accompanying drawing, in which

Fig. 1 illustrates an electrode assembly together with the supporting structure in accordance with a preferred embodiment of my invention.

Fig. 2 is a detailed view illustrating the manner in which the electrodes are clamped to the insulating supporting structure,

Fig. 3 is a view of the insulating supporting structure taken at line 3—3 of Fig. 1,

Fig. 4 is a modified form of electrode supporting structure in accordance with my invention viewed similarly to Fig. 3, and

Fig. 5 is a fragmentary view of the electrode supporting structure of Fig. 4, shown partly in cross-section to illustrate the form of the insulating supporting knob.

Turning first to Fig. 1, the flare assembly is indicated generally at 100. This assembly comprises a glass flare through which filament leads 101 may be carried by suitable metal-to-glass seals. Fastened to the glass assembly I provide a cylindrical glass member 102. This member is preferably sealed directly to the flare assembly 100, so as to form integrally therewith a portion 10 of the glass envelope. At the upper end of member 102 are provided spherical supporting knobs or members 103. A plurality of these members 103 may be provided so as to form a rigid supporting structure for the electrodes. As shown 15 in Fig. 3, four of these spherical members or knobs are provided. It is, of course, clear that any number greater than two will furnish a rigid supporting arrangement. Clamped to knobs 103 are a plurality of electrode supporting members 104. These supporting members may support a 20 grid 105, as shown in Fig. 1, or any other electrode such as an anode.

In Fig. 2 I have illustrated more completely the manner in which rods 104 are clamped onto knobs 30 103. Securely fastened to rod 104 by welding or other means is provided a solid clamping member 105.

This member flares outwardly at 106 and is preferably formed with an interior curvature 35 of spherical shape to correspond with the spherical shape of the knobs 103. Member 105 is threaded interiorly as indicated at 107. A split section cup formed of two parts 108, 109, with spherical interior faces, is provided to fit over knobs 103, the parts being so dimensioned as to 40 extend below the diameter of the knobs in order to clamp thereto. Members 108, 109, are threaded as indicated at 110, so that these portions when fitted together will thread into member 105. The threaded portions may be formed as a single unit 45 split part of its length if desired. In assembling these supports on the insulating knobs 103, members 108, 109, are first fitted around knobs 103. The solid clamp carrying with it electrode supporting rod 104, is then screwed down by these threads 107, 110, until the solid clamp member 50 engages parts 108, 109, holding them firmly in clamped position about knobs 103. This forms a rigid supporting arrangement which is easily 55

attached and detached to the insulating knobs of the tube.

With this structure completed it is clear that the electrode is supported upon knobs which are closely associated with the glass cylinder 102. It is thus clear that a strong rigid assembly is provided which is also easily and quickly assembled.

In Figs. 4 and 5, I have illustrated an alternative form of my invention. In this figure tubular member 102 is pinched at the upper end to form clamping knobs 120 which are substantially spherical in contour. However, the spheres are not complete and connection is made to the glass envelope at the lower point 121 of Fig. 5, as well as laterally of these knobs, as shown at 122, of Fig. 4. This construction is somewhat more rigid than the arrangement of Figs. 1 to 3, since the supporting knobs are braced not only at their lower edge but also at the sides. The split clamp arrangement similar to that shown in Fig. 2, may however, be easily applied to this construction. It is merely necessary that the split clamp parts be terminated short of a semi-circle so that the clamp members will fit around knobs 120 without exerting additional pressures on the walls of tube 102. It is clear that this modified arrangement still preserves the feature of easy assembly while enhancing the strength of the whole assembly.

While I have described my invention with reference to the accompanying drawing, it should be distinctly understood that this description is merely by way of illustration and not as a limitation of the scope thereof. What I consider as my invention is defined in the accompanying claims.

What I claim is:

1. A vacuum tube electrode structure, comprising a supporting member of insulating material, a plurality of knobs fixed to said member, and electrode supporting means secured to said knobs.

2. A vacuum tube electrode support, comprising a cylindrical member of insulating material,

a plurality of knobs with substantially spherical surfaces formed on one end of said cylindrical member, and electrode supporting means clamped on said knobs, whereby a rigid assembly is effected.

5

3. An electrode support comprising a plurality of spaced knob members, an electrode supporting rod for each of said knob members, and a clamp for holding each of said rods on said knob members comprising a split cup of such interior configuration as to fit closely about said knob, said cup being provided with an extended threaded portion, and a clamping member fixed to said rod and provided with an interior thread for cooperating with said threaded portion, said clamping member being provided with a flared portion for fitting about said split cup to clamp it firmly about said knob.

10

4. An electrode support, comprising a cylindrical glass unit, and a plurality of electrode supporting knobs of substantially spherical shape formed integrally on one end of said cylindrical member.

15

5. An electrode support comprising a cylindrical glass member, and a plurality of supporting knobs having spherical surfaces, formed in one end of said cylinder, said knobs having their upper surfaces substantially flush with the end of said cylinder.

20

6. An electrode support comprising a cylindrical glass member, a plurality of supporting knobs having spherical surfaces, formed in one end of said cylinder, said knobs having their upper surfaces substantially flush with the end of said cylinder, and electrode supporting members clamped to said knobs.

25

7. An electrode support comprising a cylindrical glass member, a plurality of supporting knobs having spherical surfaces, formed in one end of said cylinder, said knobs having their upper surfaces substantially flush with the end of said cylinder, electrode supporting rods, and means for clamping said rods to said knobs in close cooperation with said spherical surfaces.

LYNN GOODALE.
